UNITED STATES PATENT OFFICE.

ANKER S. LYHNE, OF BRIDGEPORT, CONNECTICUT.

ELECTRIC SWITCH.

1,122,777.

Specification of Letters Patent. Patented Dec. 29, 1914.

Application filed September 10, 1913. Serial No. 789,081.

To all whom it may concern:

Be it known that I, ANKER S. LYHNE, a citizen of the United States, residing at Bridgeport, county of Fairfield, State of Connecticut, have invented an Improvement in Electric Switches, of which the following is a specification.

This invention has for its object to provide an inexpensive, easily operated and thoroughly reliable circuit closing device particularly adapted for, although not necessarily limited to use in connection with portable electric lights, the special requirements being that the circuit be opened and closed by a short quick movement and that when closed it remain so until opened by another movement.

In order to accomplish these requirements in the simplest manner possible, I have devised the novel circuit closing and opening device which I will now describe, referring to the accompanying drawing forming a part of this specification and using reference characters to indicate the several parts.

Figure 1 is an elevation partly broken away, showing the invention as applied to an ordinary pocket light, the circuit being open; Fig. 2 a similar view showing the circuit closed; Fig. 3 an inverted plan view of the contact plate, the case being in section; Fig. 4 a plan view showing the head of the sliding stud, and the contact pin provided with a head; Fig. 5 a similar view showing a variant form of stop for the sliding stud; Fig. 6 an elevation partly broken away showing the invention applied to a tubular lamp; Fig. 7 a detail elevation of the circuit controlling device as applied to a tubular lamp; Fig. 8 a plan view corresponding therewith; and Fig. 9 is a similar view in which the head of the contact pin is omitted. Fig. 10 is a fragmentary sectional view corresponding to Fig. 2 and showing a modification.

10 denotes the case, 11 the battery, 12 and 13 the battery terminals and 14 the lamp which engages a threaded socket 15 ordinarily formed integral with the case. 50 In the form illustrated in Figs. 1 to 5, inclusive, the circuit is closed by means of a contact pin, 16 carried by a substantially straight contact spring 17 rigidly secured at one end to the inner side of the case. 55 The contact pin may or may not be provided with a head 18 by which it may be

placed in engagement with battery terminal 12 to close the circuit in the usual manner.

An important feature of the present invention consists in providing the contact spring with a recess which is normally engaged by the rounded end of a slide or sliding stud 20. Said recess may be in the form of a hole or perforation 19, as shown in Figs. 1 and 2, or of a depression 19^a, as shown in Fig. 10. This stud is provided with an external head 21 and under the head with a neck 22 which engages a slot 23 in a substantially rigid inclined guide 24 preferably formed by striking up the metal of the case. The guide 24 is arranged at an angle to the length of the spring 17 and is inclined toward the free end thereof. In order to limit the forward movement of the sliding stud, suitable stops are provided as by partly closing the lower end of the slot as at 25 in Fig. 4, or by striking up bumps at the lower end of the incline as at 26 in Fig. 5.

In the form illustrated in Figs. 6, 7 and 8, 80 the invention is shown as applied to a tubular lamp. The contact spring 27 lies outside the case which is made of insulating material and is indicated by 28. The contact spring preferably carries a contact pin 85 16 as before and this pin may or may not be provided with a head 18. The contact spring is inclosed in a housing 29 which is rigidly secured to the case and is provided with an incline 24, slot 23, and sliding stud 20 having a head 21, as before. 90 30 denotes an electrical connection extending to the lamp and 31 an electrical connection extending to the battery. These connections are rigidly secured to the case, connection 30 by means of a rivet 32, the outer end of which is in position to be engaged by the contact pin and connection 31 by means of a rivet 33, which may also secure 95 the housing to the case. 100

In Fig. 9, the head of the contact pin is omitted, it being understood of course that the head of the contact pin may be omitted in the other form as well. In this form, for convenience in assembling the sliding stud, 105 cuts are made in the metal of either the housing or the case at the lower end of the slot leaving a tongue 34 attached at the end opposite the slot. This tongue is simply sprung downward to permit the insertion 110 of a sliding stud and is then sprung back to place leaving the stud in the slot, the

lower end of the slot serving as a stop for the sliding stud.

The operation which is the same in all of the forms is as follows: The rounded end of the sliding stud normally engages the hole or depression in the contact spring. To close the circuit, the operator presses against the head of the sliding stud and forces it out of the hole or depression and causes the stud to slide down the incline, bending the spring and forcing the contact pin into engagement with either battery terminal 12 as in the first form, or with a rivet securing an electrical connection as in the second form. The circuit will remain closed so long as the sliding stud remains at the lower end of the incline, as in Fig. 2. To open the circuit, the sliding stud is moved from the position shown in Fig. 2 to the position shown in the other views, which permits the contact spring to return to its normal position and draw the contact pin out of engagement with a battery terminal of an electrical connection. By providing the hole or depression in the contact spring, which is normally engaged by the sliding stud, the sliding stud is caused to move the contact spring and contact pin part way toward the closing position, in passing out of the hole or depression, so that the remainder of the closing movement of the contact spring, and con-

tact pin may be effected by a relatively short movement of the sliding stud, it being an important feature of the invention that the opening and closing of the circuit is effected by a relatively short movement. It is wholly immaterial so far as the present invention is concerned whether or not the contact pin is provided with a head, for the reason that the sliding stud acts on the contact plate which carries the contact pin and has no co-operation with the head of the contact pin.

Having thus described my invention I claim:

In a device of the character described, the combination with a substantially straight contact spring, of a substantially rigid guide arranged at an angle to the length of said spring and inclined toward the free end thereof, said guide having a slot, and a slide directly engaging said spring and guided in said slot for movement toward the free end of said spring to move said spring into circuit closing position.

In testimony whereof I affix my signature in presence of two witnesses.

ANKER S. LYHNE.
